SUPPORT FOR VIBRATORY DEVICES

Carlo L. Calosi, Cambridge, Mass., assignor to
 Raytheon Manufacturing Company, Newton,
 Mass., a corporation of Delaware.

Application November 16, 1950, Serial No. 195,925

10 Claims. (Cl. 310—26)

1

This invention relates to tools and devices in which a vibratory element is supported from a nonvibratory platform or handling element, and more particularly to support means which rigidly connects these two elements together.

Vibratory devices for drilling, chipping, abrading, and heating materials of various kinds, operated at a wide variety of frequencies of vibration, are now well known. In copending application, Serial No. 128,989, filed November 23, 1949, there are disclosed and generically claimed two embodiments of the invention. One of said embodiments is not specifically claimed in said copending application, but is disclosed and specifically claimed herein. More recently, devices have been developed which operate at frequencies of vibration well above the upper limit of human audibility, and with forces so great that substantial heat is generated in the devices. This rapid advance in design has necessitated consideration of the problems of cooling and supporting the vibratory elements. It has thus heretofore been a practice to support the vibratory element of such a device from a nonvibratory element by means of a flexible connection, for example, a diaphragm, connected to the vibratory element at a node, in the hope that this arrangement would prevent vibratory energy from escaping from the vibratory element into the nonvibratory element. For cooling purposes, a housing is then usually arranged about the means for driving the vibratory element, the housing being attached to the nonvibratory element, and sealed watertight thereto. A cooling liquid is then passed through the housing when the device is operated.

For various reasons, the foregoing arrangement is unsatisfactory. The diaphragm, contrary to expectations, is vibrated radially when a longitudinal vibrator, passing through its center, is set into vibration. The reason for this is that, although the point of attachment of the diaphragm to the longitudinal vibrator is a node for longitudinal vibrations, the Poisson's ratio for the material of the longitudinal vibrator determines the extent of radial oscillation of the longitudinal vibrator at the node, and in materials commonly available this is quite substantial. A diaphragm support then cannot be expected to be absolutely free of vibrations. When it is realized that such a diaphragm support also forms a part of the housing through which a cooling liquid is circulated, it is immediately seen that, with the large forces which are now available, cavitation begins to appear in the cooling liquid which is in

5 contact with the diaphragm, and, as a result, the diaphragm is endangered. In addition, a diaphragm is not a rigid support, and, consequently, when a longitudinal vibrator is so supported and brought into contact with a material to be drilled, abraded, or otherwise operated upon, precision work is quite difficult; nor are these difficulties removed or lessened by slidably mounting the vibratory element in its support, for such a mounting cannot hold the vibratory element rigid and permit it to vibrate at the same time, and is in addition quite complicated.

10 In accordance with the present invention, a vibratory device is provided in which a vibratory system, consisting essentially of an element which is capable of being set into vibration and a means for driving the same, is supported from a nonvibratory element by means of a rigid, rather than a flexible, support of a kind which presents an impedance to vibrations introduced therein from the vibratory system, which impedance is low compared with that of the load into which the vibratory system is working. This combination of a rigid support having low impedance to the vibrations of the supported vibratory system provides the desired feature of rigidity without extracting appreciable energy from the working system. It has a further advantage in that only very low order vibrations occur in the supporting structure, which can then conveniently become part of a watertight housing surrounding the driving means without danger of being injured on account of cavitation in the cooling liquid.

15 Preferably, the rigid support structure is attached to the vibratory system at an antinode, rather than a node, and interposes a quarter wavelength path between the vibratory system and the nonvibratory element for vibrations at the frequency of operation. With this arrangement, the supporting structure moves with the vibratory system at the point of attachment and is still in the region of the nonvibratory element.

20 Other and further advantages of the invention, together with various modifications thereof, will become apparent from the description of a particular embodiment which follows. This description refers to the accompanying drawings wherein:

25 Fig. 1 is a side elevation partly in section illustrating an embodiment of the invention;

Fig. 2 is a section taken along line 2—2 of Fig. 1;

30 Fig. 3 is an exploded isometric view of the device shown in Fig. 1; and

Fig. 4 is a graph useful in explaining the operation of the invention.

Referring now to Figs. 1, 2 and 3, the device there shown employs a longitudinal vibratory element 10 which is driven by a magnetostrictive driving means 11, these two parts together forming a vibratory system. The driving means 11 is of a kind which is well known and consists essentially of a stack 12 of thin laminae of nickel and coils 13 of wire wound thereon which cause the laminae to undergo alternate expansions and contractions when suitably energized with polarizing direct current and alternating current of the proper frequency. The driving means 11 operates at its natural frequency with considerable force and sets the vibratory element 10 into vibration. Conveniently, the driving means 11 may have a length substantially equal to one-half a wave length therein of oscillations at the operating frequency, while the vibratory element 10 may be any integral number of half wave lengths long, being illustrated herein as substantially one whole wave length. An antinode exists in this vibratory system at the region 14 where the driving means 11 is joined to the vibratory element 10. The joining is readily effected in a well-known manner by silver soldering the two parts together, for example.

A comparatively thin tube 15, having a length which is substantially equal to one-quarter wave length therein of vibrations at the operating frequency of the device, is connected at a first end 16 to the vibratory element 10 at the region 14 of the antinode. At the other, or second end, the tube 15 is terminated in a relatively massive ring 17 which constitutes the nonvibratory element of the device. The first end 16 of the tube 15 is slightly thickened and threaded internally, and the region 14 of the vibratory element 10 which is supported therein is correspondingly threaded for engagement therewith. An extending rim or boss 18 is provided at this end of the vibratory element, and a pair of spanner wrench holes 19 in this boss is employed to bring the boss tightly up against the confronting edge of the first end 16 of the tube 15. To this end, a second pair of spanner wrench holes 20 (see Fig. 3) in the lower face of the nonvibratory element, ring 17, is provided for cooperative use in tightening the vibratory element 10 on the supporting structure. This assures that the vibratory element 10 will not be loosened during operation. The relatively thin wall of the tube 15 is substantially thickened in the region 21 close to the massive ring 17.

When the vibratory system is set into operation, the region 14 thereof, being an antinode, undergoes oscillatory longitudinal displacement at the frequency and maximum amplitude of the system. The first end 16 of the tubular support 15 moves with this region and undergoes similar displacement. However, since tube 15 is one-quarter wave length long as far as this oscillatory displacement is concerned, substantially no vibrations are impressed upon the nonvibratory support member, ring 17. Thus, ring 17 can be made massive without danger that it will absorb any energy from the vibratory system. The tube 15 enjoys the rigidity of a tubular structure and, at the same time, extracts substantially no energy from the vibratory system. In fact, if the desired dimensions are carefully observed, the region 14, in which the vibratory system is attached to the first end 16 of the tube 15, will be one of zero impedance,

as far as the supporting structure is concerned, and absolutely no energy will be passed from the vibratory system into the supporting structure. It should be emphasized in this connection that in this region the supporting structure moves with the vibratory system as though it were a part thereof. Thus, with a properly designed supporting structure, the vibratory element 10 need not be threadedly engaged with the tube 15, but actually a simple frictional fit will be satisfactory.

Referring now to Fig. 4, the curves there shown illustrate the change of impedance of the supporting structure, tube 15, with frequency under various conditions. The solid curve 23 illustrates generally the nature of this relationship. At a frequency below the resonance frequency, that is, below the frequency at which the tube 15 is a quarter wave length long, the impedance has a negative sign. As the frequency approaches resonance, the curve becomes a straight line, and, at the frequency of resonance, the impedance of the supporting structure is zero. As the frequency increases beyond that of resonance, the impedance assumes the opposite algebraic sign, but the curve 23 is still a straight line, the shape of the curve being substantially the same on both sides of resonance. The change in impedance of the supporting structure is observed from the straight line position of the curve 23. It has been found that, when the wall of the tube 15, between the first end 16 which is attached to the vibratory system and the second end at the nonvibratory element 17, is made thin, the straight portion of the curve 23 becomes nearly parallel to the horizontal axis along which frequencies are plotted, as is illustrated by the dotted line curve 24. This means that, with small changes in frequency about the frequency of resonance, the impedance of the supporting structure 15 undergoes smaller changes in value as the wall of tube 15 is thinned, or in other words that the tuning of the supporting structure is less critical. Electrically, this is equivalent to inserting an impedance in series with a parallel resonant circuit to broaden its response curve. Curve 25 illustrates an opposite situation in which the tuning of the support structure is more critical. This situation might exist, for example, if it were desired to have the wall of the tube 15 very thick for extremely rigid support under sever operating conditions, and in this case it would be desirable to observe carefully that the length of the supporting structure and its point of attachment to the vibratory system were properly chosen.

The use of a thin-wall tube 15 has been found to provide a supporting structure which is so uncritical in frequency that it can be attached to the vibratory system at regions other than an antinode without serious detriment. The reason for this is that, when the wall of the tube 15 is very thin, the amount of mass existing in a given length of support structure between the ends of the tube is greatly less than the amount of mass existing in an equivalent length of the vibratory element 10. For this reason, the impedance of the supporting structure is still very low, although it is not zero, and the amount of energy which is extracted from the vibratory system is quite small and not appreciable. Since the supporting structure is a tube, it will be ap-

preciated that the wall thereof may be made quite thin without appreciable loss of rigidity.

The nonvibratory element, ring 17, provides a convenient platform upon which to mount a watertight housing 26. The housing is in the form of a cylinder closed at one end and having a heavy ring 27 at the open end. The rings 27 and 17 are bolted together, and a gasket (not shown) may be included between them, as is well known. A tube 28 in the form of a ring and having openings 29 therein is positioned at the top of the housing 26, and an inlet 30 for cooling fluid is connected to this tube through the wall of the housing. An outlet 31 for cooling fluid is provided in the nonvibratory element, ring 17. In operation, the device is customarily supported with the closed end of the housing 26 at the top and the open end at the bottom so that a cooling liquid, water for example, may be introduced through the inlet 30 and be sprayed downwardly over the driving means 11 and supporting structure 15, and escape through the outlet 31.

The coils 13 are furnished with leads 32 which are brought through an opening 33 in the non-vibratory element, ring 17. A rigid pipe 34 is affixed in this opening and extends part way into the housing 26. For the purpose of preventing water from leaking out through the opening 33, a watertight cap 35 surrounds the leads 32 and seals the top of the pipe 34.

The device may be mounted in any convenient manner. In the event that it is desired to mount the device in a drill press, the top 36 of the housing 26 is made of substantial thickness, so that an attachment member 37, having a threaded extension 38, may be bolted thereto.

The free end 40 of the vibratory element is also at an antinode of the vibrations therein, and to this end a suitable working tool may be attached for drilling, abrading, or other purposes. Since this feature forms no part of the present invention, no further discussion of it will appear.

It is realized that various other modifications of the invention may be made without departing from the spirit and scope thereof and without the exercise of further invention, and no attempt is here made to exhaust all such possibilities. It is, therefore, intended that the claims which follow shall not be limited by the details of the embodiment herein described and illustrated.

What is claimed is:

1. In combination, an elongated mechanical vibratory system, and substantially rigid tubular support means for supporting said system loosely enveloping a portion of said system and attached at one end to said system in a region which is substantially an antinode, said support means being of a length equal substantially to an odd integral number of quarter wave lengths therein of vibrations of said system.

2. In combination, an elongated mechanical vibrator and means attached to one end thereof to set said vibrator into longitudinal oscillation, said vibrator having a length equal substantially to one or more integral half wave lengths of the vibrations therein and antinodes at its ends, a substantially rigid cylinder having low sonic dissipation and having internal diameter larger than the cross-section of said vibrator and length equal substantially to an odd number of quarter wave lengths therein of said vibrations, telescopically enveloping said vibrator and attached at an end to said one end of said member, and a ring of

comparatively great mass attached to the remaining end of said cylinder.

3. In combination, a mechanical vibratory system including an elongated vibratory element and driving means attached to one end thereof, rigid cylindrical support means attached at one end to said element substantially at the junction with said driving means, said support means extending away from said junction along said element and terminating at the other end in a ring of substantial mass which surrounds and is spaced from said element, housing means including a top and side wall means attached to said ring and forming with said support means an enclosure completely enveloping said driving means.

4. In combination, a mechanical vibratory system including an elongated vibratory element and driving means attached to one end thereof, rigid cylindrical support means attached at one end to said element substantially at the junction with said driving means, said support means extending away from said junction along said element and terminating at the other end in a ring of substantial mass which surrounds and is spaced from said element, housing means including a top and side wall means attached to said ring and forming with said support means an enclosure completely enveloping said driving means, means providing fluid passages about said side wall means near said top, means to conduct a cooling fluid into said enclosure via said passages, and means in said enclosure near the bottom thereof providing a cooling fluid outlet.

5. In combination, a mechanical vibratory system comprising a vibration source and a tapered impedance transition element coupled to said source, and substantially rigid support means attached to said system for supporting said system, the inertia of said support means to vibrations introduced therein from said system being substantially less in the region of attachment of said support means to said system than the inertia of said system in said region, said inertia of said support means gradually increasing as a direct function of the distance away from said region of attachment, said support means being substantially resonant at the operating frequency of said source.

6. In combination, a mechanical vibratory system comprising a vibration source and a tapered impedance transition element coupled to said source, having a substantially resonant operating frequency, and substantially rigid support means attached to said system substantially at an antinode of said system for supporting said system, the inertia of said support means to vibrations introduced therein from said system being substantially less in the region of attachment of said support means to said system than the inertia of said system in said region, said inertia of said support means gradually increasing as a direct function of the distance away from said region of attachment, said support means being substantially resonant at the operating frequency of said source.

7. In combination, a mechanical vibratory system comprising a vibration source and a tapered impedance transition element coupled to said source, means to set said system into vibration, and substantially rigid support means attached to said system for supporting said system, the inertia of said support means to vibrations introduced therein from said system being substantially less in the region of attachment of said support means to said system than the inertia of said system in

said region, said inertia of said support means gradually increasing as a direct function of the distance away from said region of attachment, said support means being substantially resonant at the operating frequency of said source.

8. In combination, a mechanical vibratory system comprising a source of ultrasonic vibrations, a tapered impedance transition element coupled to said source, and substantially rigid support means for supporting said system of a length equal substantially to an odd integral number of quarter wave lengths therein of vibrations of said source attached at one end to said system and terminated at the other end with a comparatively large mass, said attached end having a comparatively low mass.

9. In combination, an elongated mechanical vibratory system comprising a vibration source and a tapered impedance transition element coupled to said source, and substantially rigid tubular support means for supporting said system of a length equal substantially to an odd integral number of quarter wave lengths therein of vibrations of said source attached at one end to said transition element at a region in said system which is substantially at anti-node.

10. In combination, an elongated vibratory system comprising a vibration source, a tapered impedance transition element coupled to said source, substantially rigid tubular support means for sup-

porting said system attached at one end to said system, said support means being of a length equal substantially to an odd integral number of quarter wave lengths therein of vibrations of said source and having its wall intermediate its ends thin and of low mass compared with the mass of an equivalent length of said system, and a ring of comparatively greater mass attached to the free end of said support means, the thickness of said wall increasing gradually toward said ring.
